UNITED STATES PATENT OFFICE.

THOMAS GARRICK, OF PROVIDENCE, RHODE ISLAND.

IMPROVED SPUR FOR HORSEMAN'S USE.

Specification forming part of Letters Patent No. 39,477, dated August 11, 1863.

To all whom it may concern:

Be it known that I, THOMAS GARRICK, of the city and county of Providence, in the State of Rhode Island, have invented a new and useful Improvement in Spurs for Horsemen's Use; and I do hereby declare that the following specification, taken in connection with the drawings, making a part of the same, is a full, clear, and exact description thereof.

Figure 1 represents a boot with my improved spur attached. Fig. 2 is a view of the spur itself.

The object of my improvement is to produce spur which will fit equally well a boot-heel of any size, and which can be firmly attached without the use of straps.

A is the shank of the spur, of any shape or length which may be desirable. D is a fixed screw which forms the end of the shank, and is intended to be screwed into the heel of the boot. B is a clamp, having a spur projection, a, at each of its four corners. This clamp turns freely on the shank of the screw D, and is prevented from moving in any other direction by a shoulder in the shank of the spur on one side and by a collett, C, on the other. When the spur is to be affixed to the boot, a suitable hole is first bored in the heel of the boot, and the point of the screw D inserted. By turning the shank around the clamp will

be drawn against the heel and the projecting points a a be buried in the leather sufficiently far to hold the clamp from turning, and afford a firm hold and support for the shank. When the spur is removed, the only change in the appearance of the boot is the hole in the heel, which may be made so small as to be scarcely perceptible. In this way I am able to produce a spur which can, without inconvenience, be carried in the pocket, and which can be attached to or removed from the boot in a few seconds. The effect of the clamp B is not only to furnish a support to the spur when attached to the boot, but is also intended to compress together the lifts of leather, which form the heel, and thereby afford a better hold for the threads of the screw D.

What I claim as my invention, and desire to secure by Letters Patent, is—

The improved spur for horsemen's use described, consisting of a spur with a screw-shank, D, and a compressing and supporting clamp, B, provided with the spur-points a a a, or their equivalents, substantially as and for the purposes specified.

THOMAS GARRICK.
